G. HONEY

BELT LACING TOOL

Filed Jan. 8, 1926

Inventor
George Honey

By *Thos. S. Donnelly*
Attorney

UNITED STATES PATENT OFFICE.

GEORGE HONEY, OF CANUCK, SASKATCHEWAN, CANADA.

BELT-LACING TOOL.

Application filed January 8, 1926. Serial No. 79,975.

My invention relates to a new and useful improvement in a belt-lacing tool, and has for its object the provision of a belt-lacing tool which may be used for punching holes in 5 the leather of the belt and also for reaming out the punched holes to the proper size for the reception of the lace.

Another object of the invention is the provision of a belt-lacing tool made from a single 10 piece of metal and having a holding portion from which project a punching portion and a reaming portion, these portions projecting from the holding portion so as not to lie in alinement with each other, thus permitting 15 the use of a driving member against the holding portion to direct either of the tools into the work piece or leather operated upon when necessary.

Another object of the invention is the provision of a tool of this class which will be 20 simple in structure, economical of manufacture, and highly efficient in use.

Other objects will appear hereinafter.

The invention consists in the combination 25 and arrangement of parts hereinafter described and claimed.

The invention will be best understood by a reference to the accompanying drawings which form a part of this specification and 30 in which,

Fig. 1 is a side elevational view of the invention,

Fig. 2 is a sectional view taken on substantially line 2—2 of Fig. 1, and

Fig. 3 is a sectional view taken on substantially line 3—3 of Fig. 1.

As shown in the drawings the invention comprises a tool formed from a single piece of metal, preferably cylindrical and so arranged 40 as to provide a circular holding portion 8, the ends of the metal overlapping to provide the adjacent portions 9 and 10. One of the ends of the metal is projected outwardly, preferably diametrically, from the holding portion 8, this end 11 being tapered to a point at the free end 12, and swaged to provide this outwardly projecting portion with an arcuate formation having the concave side 13 and the ends 14 and 15 of this 45 arcuate portion being sharpened so as to provide cutting edges for reaming the hole 50

punched in the belt. The opposite end also projects outwardly, diametrically, from the holding portion, and preferably at right angles to the line of projection of the end 11. 55 This end 16 is formed circular in cross-section and reduced toward its end to provide a point 17, this end being used for a punch or as an awl for punching holes in the leather so that the reaming end may be easily inserted into the leather. 60

At the present time the operator in lacing a belt is provided with an awl and a reaming tool which are separate. This necessitates the operator laying one tool down after use 65 before using the other tool, with a consequent loss of time. It is also believed that the present device, embodying the two tools, may be manufactured more cheaply than the two separate tools, inasmuch as the separate awl 70 and reamer are each provided with a suitable handle.

By providing the holding portion 8 in the manner described a sufficient surface is presented for the operator to grasp the device 75 and operate it by hand. When desired the hand-hold may be struck with a hammer or other device to force the awl or reamer into the leather. By projecting the ends from the holding portion diametrically a direct blow 80 may be struck on the holding portion directly in line with the tool to be driven. By directing these ends diametrically at right angles to each other the possibility of distorting the holding portion is lessened as the striking on 85 the holding portion for driving one tool is offset by the driving required to force the other tool into the leather.

While I have illustrated and described the preferred form of structure, I do not wish 90 to limit myself to the precise details of structure set forth but desire to avail myself of such variations and modifications as come within the scope of the appended claims.

Having thus described my invention what 95 I claim as new and desire to secure by Letters Patent is:

1. A belt-lacing tool of the class described, comprising a single piece of metal having the main body doubled upon itself into circular 100 form to provide a holding portion, the ends of said metal being projected outwardly from

said holding portion diametrically thereof and at right angles to each other, one of said ends being formed into a tool tapered toward its end and concave in cross-section.

5 2. An article of manufacture, comprising a single piece of wire having the main body coiled upon itself into a circular form and

the ends projecting diametrically outwardly therefrom at substantially right angles to each other, each of said ends being tapered toward its end. ¹⁰

In testimony whereof I have signed the foregoing specification.

GEORGE HONEY.
